(57) **CLAIM**

The ornamental designs for a nose and mouth face mask, as shown and described.

DESCRIPTION

FIG. 1 is a perspective view of a first embodiment of the nose and mouth face mask;

FIG. 2 is another perspective view thereof;

FIG. 3 is a front view thereof;

FIG. 4 is a rear view thereof;

FIG. 5 is a right-side view thereof;

FIG. 6 is a left-side view thereof;

FIG. 7 is a top view thereof;

FIG. 8 is a bottom view thereof;

FIG. 9 is a perspective view of a second embodiment of the nose and mouth face mask;

FIG. 10 is another perspective view of the second embodiment;

FIG. 11 is a front view of the second embodiment;

FIG. 12 is a rear view of the second embodiment;

FIG. 13 is a right-side view of the second embodiment;

FIG. 14 is a left-side view of the second embodiment;

FIG. 15 is a top view of the second embodiment; and,

FIG. 16 is a bottom view of the second embodiment.

The broken lines in the drawings illustrate portions of the nose and mouth face mask and form no part of the claimed design.

1 Claim, 8 Drawing Sheets
